(57) **CLAIM**

The ornamental design for a corner rail extrusion, as shown and described.

DESCRIPTION

FIG. 1 is a perspective view of a corner rail extrusion of the present invention;

FIG. 2 is an end elevation view, the opposite end being a mirror image thereof;

FIG. 3 is a left side elevation view thereof, the right side elevation view being a mirror image thereof;

FIG. 4 is a rear elevation view thereof; and,

FIG. 5 is a front elevation view thereof.

The corner rail extrusion is shown with a symbolic break in its length. The appearance of any portion of the corner rail extrusion between said break lines forms no part of the claimed design.
